UNITED STATES PATENT OFFICE.

WILLIAM HARRIS, OF AUBURN, MASSACHUSETTS.

MECHANISM FOR ATTACHING SHEETS OF CARD-CLOTHING TOGETHER AND TO THE GRINDING-CYLINDER.

SPECIFICATION forming part of Letters Patent No. 413,445, dated October 22, 1889.

Application filed May 20, 1889. Serial No. 311,483. (No model.)

To all whom it may concern:

Be it known that I, WILLIAM HARRIS, of Auburn, in the county of Worcester and Commonwealth of Massachusetts, have invented 5 certain new and useful Improvements in Fastening Mechanism for Securing Sheets of Card-Clothing Together and to the Grinding-Cylinder; and I do hereby declare that the following is a full and clear description of the 10 same, reference being had to the accompanying drawings and the letters of reference marked thereon, forming a part of this specification, and in which—

Figure 1 represents a plan view of my fastening mechanism when applied to use, as will 15 be hereinafter more fully described. Fig. 2 represents an end view of the parts shown in Fig. 1, as hereinafter described. Fig. 3 represents, upon an enlarged scale to that shown 20 in Figs. 1 and 2, a section of card-clothing on each side of the tightening mechanism, a plan view, as will be hereinafter more fully described, the straps being shown attached together. Fig. 4 represents a section on line *a*, 25 Fig. 3, looking in the direction indicated by the arrow, Fig. 3, before the straps are fastened together. Fig. 5 represents a section on line *b*, Fig. 3, looking in the direction indicated by the arrow, Fig. 3, the straps being 30 fastened together and to the cylinder. Fig. 6 represents a section on line *c*, Fig. 3, as will be hereinafter more fully described.

To enable those skilled in the art to which 35 my invention belongs to make and use the same, I will now describe the invention more in detail.

It is desirable to grind the teeth of card-clothing before it is sold or sent away from the manufactory, and for several reasons, 40 among which may be mentioned the danger from fire when the teeth are not ground until the sheets have been secured to the cards in the mill; further, there is great loss of time when the first grinding takes place in the mill. 45 The modes heretofore in use have not proved free from serious objections; and it is the object of my present invention to improve and perfect the mechanism employed in the process or method of preparing sheets of card-clothing for grinding before the said sheets 50 are attached to the cards, and which method

forms the subject-matter of a separate application for Letters Patent filed April 2, 1888, Serial No. 269,302, and is not, therefore, claimed in this application, which is limited 55 to the mechanical devices hereinafter described.

In the drawings, the parts marked B are the sheets of leather, cloth, or other material, in which the teeth *d* are set in the usual and 60 well-known manner. It may be stated, however, that each blank sheet or back B is strained taut between rigid jaws or clamps, and thus held until all the teeth in such sheet have been set. Consequently the teeth all 65 stand in a certain relative position to each other, and it is desirable that when first ground they should be retained in such positions.

Heretofore it has been the practice in some 70 factories for setting card-teeth to sew the separate sheets to an endless belt of cloth or other flexible material and then run the same over cylinders which supported the same, while emery-wheels properly arranged and 75 operated ground the teeth; but in this way the sheets were not held true and even, consequently the teeth were left imperfect. In other cases the sheets have been fastened to 80 the cylinder by clamping devices fastened to the cylinder, each sheet being fastened to the cylinder in an independent manner, and which involved complicated mechanism that was liable to get out of order, and, besides, the 85 sheets were not held in the same relative manner to insure the teeth in the proper and most desirable positions while being ground. Then, again, when the cylinder which supports the card-clothing while being ground is bored full of holes, a separate 90 cylinder must be employed for each width of sheet otherwise all the holes not used must be plugged and smoothed off, or the backs of the teeth resting over such holes will be pressed into the same, and these teeth will 95 thus be unground, or ground in an imperfect manner, besides being uneven.

In the drawings only a portion of the sheets B are shown with teeth *d*; but it will be understood that the others also have teeth, those 100 shown serving to illustrate my invention.

To fasten the sheets together so that each

sheet will support its respective teeth in the same relative position in which they were set, I have a clamping device consisting of a top metal clamp-piece C, which is a little longer than the sheet to be ground, and is concave on the under side, and is provided with clamping or side-holding jaws C' e g, to act in combination with the under clamping-piece C², which is provided with side clamping-wings f h, and these parts when in use are held together by means of holding-screws C³. The sides of the upper part of the clamping-piece C² are made parallel to each other, and against which the edges of two adjacent sheets B abut, and are securely held when screws C³ are in place, as indicated in the drawings. A set of card-clothing sheets B, as they come from the card-setting machine, are fastened together, a suitable table or platform being used, and each sheet is held in the same position by its two sides or edges as it was held in the jaws of the card-setting machine. This is an important point, since the greatest success depends upon the sheets being held and fastened together and to the grinding-cylinder without twisting.

I will now describe the mechanism for fastening the sheets thus fastened together to the cylinder A preparatory to grinding the teeth in a uniform manner.

I have one set of clamping devices for clamping the first edge of the first sheet B, as shown on the right-hand end of each of the Figs. 3, 4, 5, and 6, and to the left side of this clamping device is attached the metal tightening-strap F by means of two screws F' F', which pass through both of the clamping-pieces C and C². The edges of jaw C'—the parts e and g—are cut away for the reception of the end of strap F. (See Figs. 4 and 5 of the drawings.) It will be seen that a part of the under side of jaw C' e g is cut away to receive the end of strap F, and when the first sheet B (shown on the right) is placed between the clamping-pieces C and C² pieces of leather of the same thickness as sheet B are placed between the jaws on each side of the straps F, as indicated by dotted lines, Fig. 1, two straps F being used, and each strap is placed about one foot from each end of the clamping devices. To the clamping device attached to the last sheet B (shown on the left in Figs. 3, 4, and 5 of the drawings) another set of straps E is attached, one of which is shown upon an enlarged scale in Figs. 3, 4, and 5 to what the same parts are shown in Figs. 1 and 2. Strap E is fastened to clamping-pieces C and C² by a single screw E'. The under side of jaw C' e g is cut away a little more to receive strap E, as seen at i, than the same or corresponding parts are cut away, as seen at j, to receive the strap F, it being desirable to give strap E some play up and down. Pieces of leather are placed between the clamping-pieces on each side of straps E (see dotted lines, Fig. 1) when the last sheet B is attached, same as in the case

of the attachment of the first sheet, as before stated, and by which arrangement the clamping-pieces are kept true and even when screwed together to hold the first and last sheets. As the clamping devices C and C², when secured together are stiff and rigid, they hold all the card-sheets in an even true relative position, no twisting of sheets or teeth. It being understood that the operator has all the sheets of card-clothing to make a set clamped together and is ready to attach the same to the cylinder A, he then fastens the straps F F to the surface of cylinder A by means of screws L, one to each strap F, after which cylinder A is revolved and the entire series of clamped sheets wound upon the cylinder, when strap E is placed over strap F, as shown in Fig. 4, and a tightening-lever J, the upper end of which is shown broken off in Fig. 4, is inserted through one of the slots H and its lower end entered into one of the holes I and strap E drawn over strap F, and the operation repeated until the series of sheets of card-clothing B are all drawn to the desired tautness, when screw M is inserted through a hole in the plate E and screwed into one of the holes K in plate or strap F, whereby the straps or plates E and F will be securely fastened together, and also to cylinder A, with the series of sheets B of card-clothing, and all of which are now ready to be ground by means of grinding-rolls made and operated in the well-known manner, and therefore no further description of the grinding operation is here necessary, it being understood that cylinder A is rotated by power applied to its shaft A', which is also supported and rotated in the well-known manner. Arrows indicate the direction in which the cylinder A and its sheets of card-clothing move, also that of the grinding-rolls D, which grind the teeth d.

It will be observed that the holes I on one side of holes K alternate with the holes I on the other side of holes K, whereby a tightening-lever J can be inserted on alternate sides of holes K, and a great and very even strain obtained on the strap or plate E and the series of card-sheets B, screw L holding the first set of clamps C C² fast to cylinder A.

By having strap E attached to its clamp device C C² loosely its outer end can be raised up, as shown in Fig. 4, to allow lever J to be inserted in an inclined position, (see Fig. 4,) whereby a great leverage is obtained in the tightening operation. Straps E and F may be made of any desired length, and more or less holes K and I may be formed in the strap F, and, if preferred, more than two slots H may be made in strap E. By my invention there need be but two holes in the cylinder A, those for the screws L, one for each strap F. If, therefore, a cylinder A is made large enough for a full set of card-sheets of the greatest width of sheets used, the same cylinder can be employed for grinding all sheets of less width, false pieces of leather being

put in to give the desired length to reach around the cylinder to enable the straps E and F to lap each other to fasten, as shown in the drawings. The backs of all the teeth d 5 will always rest on the smooth surface of cylinder A during the grinding operation.

The invention is simple and effective.

Having described one good and practical way for carrying out my said invention, what 10 I claim as new and of my invention, and desire to secure by Letters Patent, is—

1. The combination, with a series of clamping-pieces C C², provided with holding-jaws e 15 and clamping-wings f h, respectively, of a series of sheets of card-clothing B, the sheets of card-clothing and clamping-pieces being arranged alternately and parallel to each other and held securely in such relative positions by screws C³, substantially as and for 20 the purposes described.

2. The combination of tightening-straps E and F, with their respective clamping-pieces C and C², substantially as and for the purposes set forth.

3. Clamp C, having one side provided with 25 jaws e g and the other side provided with recesses, in combination with straps E F, strap E being provided with slots H, and perforated for attachment to its clamp, and strap F being provided with the series of holes I K, and 30 with perforations for attachment to its clamp and to the cylinder, substantially as described.

WILLIAM HARRIS.
